(57) **CLAIM**

The ornamental design for a rectangular jewelry enhancer, as shown and described.

DESCRIPTION

FIG. 1 is a front and right side perspective view of a rectangular jewelry enhancer.

FIG. 2 is a front view of a rectangular jewelry enhancer.

FIG. 3 is a rear view of a rectangular jewelry enhancer.

FIG. 4 is a left side view of a rectangular jewelry enhancer.

FIG. 5 is a right side view of a rectangular jewelry enhancer.

FIG. 6 is a top view of a rectangular jewelry enhancer; and,

FIG. 7 is a bottom view of a rectangular jewelry enhancer. The broken lines shown in the drawings illustrate portions of the rectangular jewelry enhancer that form no part of the claimed design.
